UNITED STATES PATENT OFFICE

STANISLAV HACKENBERG, OF SAN FRANCISCO, CALIFORNIA, ASSIGNOR OF ONE-HALF
TO NAFANAIEL HACKENBERG, OF SAN FRANCISCO, CALIFORNIA

TURBINE

Application filed June 14, 1929. Serial No. 371,037.

The present invention relates to improvements in turbines and its principal object is to provide a turbine that is simple in construction and economic in operation.

5 A further object of the invention is to provide a turbine in which the direction of rotation of the main shaft may be easily and quickly reversed.

10 Another object of the invention is to provide a turbine of the character described that is extremely rugged in construction and in which power is transmitted to a shaft running at right angles to the drive shaft in a particularly efficient manner.

15 Further objects and advantages of my invention will appear as the specification proceeds.

The preferred form of my invention is illustrated in the accompanying drawing, in 20 which

Figure 1 shows a side elevation of my turbine;

Figure 2, a longitudinal vertical section through the same;

25 Figure 3, a transverse section taken along line 3—3 of Figure 2;

Figure 4, a transverse section taken along line 4—4 of Figure 2;

30 Figure 5, a horizontal section taken along line 5—5 of Figure 2; and

Figure 6, a perspective detail view of an operating member for covering and uncovering and uncovering ports.

While I have shown only the preferred 35 form of the invention, I wish to have it understood that various changes or modifications may be made within the scope of the claims hereto attached without departing from the spirit of the invention.

40 The casing 1, which may be partly filled with oil, as indicated at 2, has a shaft 3 supported therein in journals 4 extending through the casing and supported in opposite walls thereof. The shaft 3 has a worm 5 thereon, which meshes with a worm gear 6 on a transverse shaft 7.

In adjacent relation to the housing 1, there is provided a second housing 8 fastened to the first housing by means of bolts 9, and 50 one end of the shaft 3 extends into the second

housing and terminates within the same in a drum 10, which is revolvably mounted on a cylinder 11 extending into the second housing from the opposite side and in coaxial relation with the shaft 3, this cylinder having a 55 cap 12 for closing the same and being fastened to the housing by means of bolts 13. The drum 10 is formed with two annular series of blades 14 and 15 arranged parallel to one another with the blades inclined in opposite directions, as appears particularly well from a comparison of Figures 3 and 4. The blades are inclined in such a manner that a pressure medium active on the blades from the inside of the drum causes the drum to rotate in one direction or the other, according to which set or series of blades is used. The cylinder 11 is formed with two parallel 60 series of perforations 16 and 17, the two series registering with the two series of blades respectively, so that steam or whatever pressure medium is used may be discharged through the perforations against the blades, the amount of steam discharged depending 65 upon the number of perforations left uncovered.

70 For each set of perforations, there is provided a sliding valve such as shown in perspective view in Figure 6, the two valves being shown in Figure 2 at 18 and 19 respectively. Each of these valves comprises a segment of a bar 20 curved to conform to the circumference of the cylinder 11 and formed with a plurality of teeth 21 in the inner face and two flat wings 22 extending from the sides for widening the outer bearing face, the length of the wings coinciding with the space occupied by the perforations 16 or 17, so that all the perforations may be covered at one time. The two segments 18 and 19 are actuated by two pinions 23 and 24 respectively, which latter are supported on longitudinal 85 shafts 25 and 26 extending into the cylinder through the cover 12 and supported in bearings 27 in the far end of the cylinder.

90 Each of the shafts 25 and 26 has a hand wheel 28 thereon. It will be noted that by operation of either one of the hand wheels, one of the segments is operated and is made to cover or uncover one or more ports 16 or 100

17. The outer face of each segment, as far as the latter extends beyond the wings 22, is formed with transverse grooves 29 to allow free access of the steam or other pressure medium through the perforations 16 or 17 when the same are not covered by the wings 22.

5 The segments are suitably guided in guideways 31, 32 and 33.

A ring 34 is slidably mounted on the drum 10 for covering either one of the two sets of blades and is actuated by a rod 35 slidably mounted in bearings, indicated at 36 and 37, and operated by a handle 38 pivoted to the housing, as shown at 39, and connected to a cross member 40 extending from the rod 35 by means of a link 41. Diametrically opposite the rod 35, a guide rod 42 is provided in the housing 8 for guiding the ring 34, which latter is formed with ears 43, (see Figure 3) for accommodating the rods 35 and 42.

20 The steam or whatever pressure medium is used enters into the cylinder 11 through the intake port provided at the front end at 44 and is exhausted through a discharge port 25 formed in the bottom of the housing 8.

The bearing 4 for the shaft 3 in the housing 1 is covered by a cap 46 adapted to receive the oil that may be carried by the worm gear 6, the worm 5 and the shaft 3 through the 30 bearing, and a return passage for this oil is provided at 47.

The turbine described hereinabove operates as follows:

The operator, by manipulating the handles 35, 28, first covers one set of perforations 16 or 17 according to the desired direction of rotation of the shaft 3 and covers or uncovers as many of the perforations of the other set as he may deem necessary for the development 40 of the power required. He then, by operating the lever 38, covers the set of blades corresponding to the previously-covered set of perforations, so that only one set of perforations and blades are exposed. He then

45 turns the steam or whatever pressure means he uses into the cylinder 4, and the steam passing through the perforations 16 or 17 discharges against the blades of one series, causing the drum 10 to rotate, whereby the shaft 50 3 is rotated and rotation is transmitted to the shaft 7 through the worm 5 and the worm gear 6.

55 For reversing the direction of rotation, it is only necessary to shift the lever 38 for uncovering one set of blades and covering the other set; to manipulate the wheels 28 for covering the set of perforations previously used and for uncovering the other set.

I claim:

60 1. In a turbine engine, a revolvably mounted drum slotted to present two parallel series of blades inclined in opposite directions, a fixed cylinder serving as bearing for the drum and having two series of perforations 65 registering with said blades, means for dis-

charging a pressure medium through said perforations against the blades and means for rendering either series of perforations and blades inactive, including means for adjusting the port area of each series of perforations.

2. In a turbine engine, a revolvably mounted drum slotted to present two parallel series of blades inclined in opposite directions, a fixed cylinder serving as bearing for the 75 drum and having two series of perforations registering with said blades, means for discharging a pressure medium through said perforations against the blades, means for rendering either series of perforations and 80 blades inactive, including means for adjusting the port area of each series of perforations and means for covering the blades from the outside of the drum.

3. In a turbine engine, a fixed cylinder having 85 a row of openings, a revolvably mounted drum having a plurality of slots forming blades and registering with the row of openings, means for directing a medium against the blades and from the inside of the cylinder, means for covering the cylinder openings from the inside, and means for covering the drum blades from the outside.

4. In a turbine engine, a fixed cylinder having 90 a row of openings, a revolvably mounted drum having a plurality of slots forming blades and registering with the row of openings, means for directing a medium against the blades and from the inside of the cylinder, means for covering the cylinder openings 100 from the inside, and means for covering the drum blades from the outside, said cylinder blade covering means being adjustable for varying the quantity of medium admitted to the blades.

5. In a turbine engine, a fixed cylinder having 105 two rows of openings, a drum rotatably mounted on the cylinder and having two sets of blades registering with the two rows of openings, one set of blades being inclined oppositely to the other set for rotating the drum in either direction, means for directing a medium against the blades from the inside of the cylinder, means for entirely closing off communication of the medium to either set of 110 cylinder openings or for partially closing such communication, and means for covering either one of the sets of drum blades.
